**LARGE DIAMETER ROTATING BLADE AND
CONTACT ASSEMBLY**
Ludolph M. Larsen, Minneapolis, Minn., assignor, by
mesne assignments, to the United States of America
as represented by the Secretary of the Navy
Filed Nov. 7, 1962, Ser. No. 236,173
11 Claims. (Cl. 200—15)

This invention relates to a multi-conductor slip ring of relatively large diameter and more particularly to a slip ring for use in connection with a guided missile launching system magazine, which features novel means of construction to obtain accurate spacing of contacts, compensation for axial displacement between fixed and rotating members, and a novel arrangement of contact assemblies and brush assemblies to facilitate installation of the slip ring between the fixed and rotating structures which it serves.

More specifically, the invention consists essentially of a pair of identical contact blade assemblies one of each of the assemblies being mounted in an aperture provided in a fixed inner structure and disposed in predetermined spaced relationship and eight identical brush assemblies, each assembly being mounted in an aperture provided in an inner wall of a rotatable member such, for example, as a conventional ready service ring or missile cell structure and disposed in predetermined spaced relationship about the aforesaid inner wall.

During the launching operations of guided missiles, warmup cycles are necessary prior to the hoisting of the missiles from the missile cells onto the launching arms of the missile launcher. Accordingly the device of the present invention makes possible the exchange of warmup power and indication signals between the launching system control and the missiles on the rotatable magazine or ready service ring. Primarily, warmup control consists of putting a selected number of missiles on warmup positions and maintaining this number on warmup. Two things affect missile warmup once it has been initiated, a missile on warmup may be loaded onto the launcher or the missile on the warmup may reach the maximum warmup time limit. In either case, a new (cool) missile must be put on warmup to maintain the selected number on warmup. Warmup is removed at the hoist position when the missile is hoisted onto the launcher, or when it has reached the maximum time limit on warmup. Thus it is an object of the present invention to automatically establish warmup circuits to a selected number of missiles prior to a hoisting and launching operation.

Another object of the invention is to provide a slip ring which features novel means of construction to obtain accurate spacing of contacts and compensation for axial displacement between fixed and rotating member.

Still another object of the invention is to provide a multi-conductor slip ring having a novel arrangement of contact assemblies and brush assemblies to facilitate installation of the slip ring between the fixed and rotating structures which it serves.

Still another object of the invention is to provide an electrical contact ring which makes possible the establishing of warmup power to missiles supported in a rotatable magazine.

A still further object of the invention is to provide a multi-conductor device wherein alignment and proper electrical contact between the brush fingers and contact blades are assured.

Other objects, advantages and novel features of the invention will become apparent from the following detailed

2

description of the invention when considered in conjunction with the accompanying drawings wherein:

FIG. 1 is a longitudinal sectional view of a guided missile launching structure illustrating the device of the present invention mounted thereon;

FIG. 1A is an enlarged sectional view of a portion of the structure of FIG. 1;

FIG. 2 is a cross sectional view taken substantially on the line 2—2 of FIG. 1 illustrating the position of components of the slip ring with respect to rotatable ready service ring and the fixed inner supporting structure;

FIG. 3 is an enlarged plan view partially in elevation and partially in section of one of the contact blade assemblies and one of the brush assemblies of the present invention;

FIG. 3A is an enlarged, exploded, perspective view of portions of the blade and brush assemblies of FIG. 3, and looking substantially to the right in FIG. 3;

FIG. 4 is a cross sectional view taken substantially on the line 4—4 of FIG. 3;

FIG. 5 is a front view of the brush assembly partially in elevation and partially in section; and

FIG. 6 is a view in perspective illustrating the general arrangement of the contact and brush assemblies of the present invention.

Referring now to the drawings and more particularly to FIG. 1, FIG. 1A and FIG. 2 thereof, the numeral 10 generally indicates a conventional missile magazine structure comprising an inner fixed tubular structure 11 and an outer ready service ring or missile container 12, which rotates about the inner structure 11 upon two radial roller bearings 13 whereby its axial position is maintained with respect to the inner structure 11, the container 12 being driven in any conventional manner such, for example, as by a motor M and gear arrangement G. The vertical position of the ring 12 is positioned by rollers 14 which engage and roll on the outer magazine structure, as at 15, the ring 12 being provided with inner and outer cells 16 and 17 in which the missiles are supported, as best shown in dashed outline in FIG. 1.

In practice the device of the present invention operates in a closed annular chamber 19 formed between the outer wall 21 of the inner structure 11 and the inner wall 22 of the rotatable ready service ring 12 and between two mutually spaced radially disposed bearings 13, FIG. 1. This device consists essentially of two identical contact blade assemblies 24 and 25 mounted on the wall 21 of the inner structure 11 and eight identical brush assemblies 26, 27, 28, 29, 31, 32, 33, and 34 mounted on the inner wall 22 of the structure 12.

As more clearly shown in FIGS. 3 and 4 each contact assembly is disposed in an opening 35 formed in the wall 21 of the inner structure 11 and comprises a plate or support 36 secured to the wall 21, as by screws or the like 37. The plate 36 carries a solid block 38, composed of any insulating material suitable for the purpose such, for example, as hard rubber or the like, the block being provided with an arcuate outer surface 39 into which a plurality of slots 41 and 42 are formed.

Each of the slots 41 has disposed therein a contact blade 43 and each of the slots 42 has disposed therein an insulating strip or separator 44, the blades and strip being secured in their respective slots with a suitable adhesive compound. A guide rail 45 is carried by the block 38 and mounted above and parallel to the contact blades, the block being secured to the plate 36 as by screws or the like 46. The plate 36 of each contact assembly has secured thereto, as by screws 47, a housing 48 which housing encloses a plurality of electrical terminals 49, the

terminals in one contact assembly being electrically connected to corresponding terminals in the other contact assembly and with their respective contact blades 43, thereby to establish an electrical connection therebetween. The electrical connection between the contact blade assemblies is established by a pair of cables 51, as best shown on FIGS. 2 and 6.

Each brush assembly of the present invention comprises a casing 52 disposed within an opening 53 formed in the wall 22 of outer structure or service ring 12 and is secured thereto by screws or the like 54. A brush support indicated generally by the reference character 55 and comprising a pair of end strips or members 56 and a center strip 57 is mounted in casing 52, the strips being composed of any suitable insulating material. It is to be noted that the brush supports 55 are within opening 53 formed in the casing 52 as best shown in FIG. 3. The center strip 57 is provided with a plurality of slots 59 disposed in staggered relationship for receiving brush fingers 61, the brush fingers being secured within the slot by a rib 62 formed on each strip 56 and disposed in a notch or recess 63 formed in the brush fingers 61, as best shown on FIGS. 3 and 3A. The strips 56 and 57 are secured together by a plurality of bolts 64 and to facilitate slight vertical movement of the strips 56-57 and the brushes 61, a plurality of pins 65 extend through the strips with the terminal ends thereof disposed in slots 66 formed in brackets 67 as shown in FIGS. 4 and 5. The brackets are secured to the casing 52, as by screws 68 and border on the aforesaid opening or slot 53 therein, as best shown on FIG. 3. A cross block 69 with tapered ends 71 extends across the strips 56 and 57 and is fastened thereto, as by screws or the like 72, the block 69 being engageable with a groove 73 formed in the guide rail 45 carried by the plate 38 of the contact assemblies, FIGS. 4 and 5 thereby to align the brushes with the contact blades as the brush assembly rotates past the contact assembly.

Each casing 52 of the brush assemblies, for example 26, is provided with five rotary relays one of which is shown in FIG. 3 and designated by the reference character 74. These relays are adapted to function during a warmup cycle. One relay is in the warmup circuit of each missile. To establish an electrical connection between the brushes and the relays in each casing terminal boards 75 are supported within the casing 52, as by brackets 76, secured to the casing, as at 77. Electrical cables 78 establish connections between the aforesaid brush assemblies.

It is to be noted in FIG. 3 that the casings 52 of the brush assemblies are each provided with a pair of access openings 79 and 81, each opening being closed by a cover or plate 82 secured to the casing, as by screws or the like 83, the aforesaid arrangement being adapted to provide easy access to the interior of the casing so that electrical connection may be made between the elements of the brush assemblies.

As more clearly shown in FIG. 3, both the contact assemblies and the brush assemblies are disposed in a direction facing outwardly from the center of the inner structure. Since the contact assemblies are larger than the brush assemblies, both can be installed and removed for servicing from the inside of the inner structure. It will be further noted in FIG. 2 that the eight brush assemblies are equally spaced about the wall 22. In accordance with this spacing, a single contact blade assembly subtending slightly more than a 45 degree arc would be functionally sufficient. In the design, however, two contact segments of approximately 26 degrees of arc are used to reduce the size of the material stock required and also the two nearly square apertures in the inner structure require less reinforcing than would a single aperture twice as wide.

In accordance with the present invention there are 50 contact blades in each contact assembly and 50 brushes

in each brush assembly. The corresponding contact blades are connected in series, as are corresponding brushes. As can be seen in FIG. 2, if the ready service ring is rotated clockwise, brushes 61 in assembly 27 have 5 engaged contact blade 43 in assembly 25, before brushes 61 in assembly 26 have disengaged from contact blade 43 in assembly 24 and brushes 61 in assembly 34 will engage contacts 43 before brushes 61 in assembly 25 have disengaged contacts 43 in assembly 27. It will be understood that when the brushes of a brush assembly are about to contact the blades of a contact assembly, the guide block 69 of the brush assemblies enters the groove 73 in guide rail 45 of the contact assemblies and invariably aligns the brushes and blades, so that the brushes are forced open and slide along the top and bottom of the contact blades, as more clearly shown in FIG. 4. It is to be further understood that each level of contacts in each brush assembly is connected to the same level of contacts in the adjacent assembly, so that any brush assembly in 10 contact with the blades of a contact assembly feeds power to all other brush assemblies. In effect, the warmup electrical contact ring functions as an electrical slip-ring.

Obviously many modifications and variations of the present invention are possible in the light of the above 15 teachings. It is, therefore, to be understood that within the scope of the appended claims the invention may be practiced otherwise than as specifically described.

What is claimed is:

1. In a multi-conductor device of the class described, 20 in combination,

a fixed inner tubular member, a rotatable outer member; 25 a pair of contact assemblies mounted on said fixed inner tubular member and having a plurality of contact blades carried thereby; a plurality of brush assemblies mounted on said rotatable member and having a plurality of brush fingers carried thereby, the brush fingers on at least two of said assemblies cooperating with said contact blades on said pair of contact assemblies as the outer member rotates about said inner member; guide means on the contact assemblies; complementary guide means on the brush assemblies engageable with the guide means on the contact assemblies for invariably aligning the brush fingers with contact blades as the brush assemblies rotate past the contact assemblies; and means carried by said brush assemblies for allowing vertical movement of the brush fingers as the fingers engage the contact blades on the pair of contact assemblies.

2. In a multi-conductor device of the class described, 30 in combination;

a fixed inner tubular member, a rotatable outer member,

a pair of mutually spaced blade supports secured to said tubular member,

a plurality of contact blades carried by each blade support of said pair of blade supports,

a plurality of brush supports secured to said outer member,

a plurality of brush fingers carried by one of each of said plurality of brush supports and cooperating with said contact blades as the brush supports rotate past said blade supports,

guide means carried by each blade support of said pair of blade supports,

complementary guide means carried by each brush support of said plurality of brush supports and engageable with the guide means on said blade supports, for invariably aligning the brush fingers with the contact blades upon movement of the brush supports past the pair of blade supports; and means including pin means carried by each brush support of said plurality of brush supports for allowing

vertical movement thereof and the brush fingers thereon as the fingers engage the contact blades on the pair of supports.

3. In a multi-conductor device of the class described, in combination,

- a fixed inner tubular member;
- a rotatable outer member;
- a pair of mutually spaced plates secured to said tubular member;
- an insulating member carried by each plate of said pair of plates;
- a plurality of contact blades carried by the insulating member on each plate;
- a plurality of mutually spaced casings carried by and secured to said rotatable outer member;
- 15 a movable support carried by each casing of said plurality of casings;
- a plurality of brush fingers carried by the support in each casing and cooperating with the contact blades on said insulating member on each plate as the outer member rotates about said inner member;
- 20 guide means carried by each plate of said pair of plates; complementary guide means carried by the movable support of each casing and cooperating with the guide means carried by each plate for invariably aligning the brush fingers with the contact blades upon movement of the casings past each plate of said pair of plates; and means on said movable support of each casing and movably mounted thereon for allowing vertical movement thereof and the brush fingers 25 thereon as the fingers engage the contact blades on the insulating member on each plate of said pair of plates.

4. The combination of structure according to claim 3 wherein said guide means includes a guide block carried by each plate;

- a guide rail carried by the movable support of each casing engageable by said guide block of each plate.

5. The combination of structure according to claim 3 wherein said means on the movable support of each casing includes a plurality of pins carried by each movable support and having the terminal ends thereof disposed in cooperating slots formed in the casings.

6. In a multi-conductor device of the class described, in combination,

- a fixed inner tubular member;
- a rotatable outer member;
- a pair of mutually spaced plates carried by and secured to said tubular member;
- an insulating member carried by each plate of said pair of plates;
- a plurality of equally spaced contact blades carried by the insulating member on each plate and having an insulating strip disposed therebetween;
- a plurality of mutually spaced casings carried by and secured to said outer rotatable member;
- 55 a movable support carried by each casing of said plurality of casings;
- a plurality of brush fingers carried by the support of each casing and cooperating with the contact blades on the insulating member on each plate as the outer member rotates about the inner member;
- a guide rail carried by each plate of said pair of plates and having a groove therein;
- a guide block carried by the movable support of each casing engageable with the groove in each guide rail for invariably aligning the brush fingers with the contact blades upon movement of the casings past each plate of said pair of plates, and
- 65 means on the movable support of each casing engageable with complementary means thereon for allowing vertical movement of the supports and the brush fingers thereon as the fingers engage the contact blades on the insulating member on each plate of said pair of plates.

7. In a multi-conductor device of the class described, in combination,

- a fixed inner tubular member,
- a rotatable outer member,
- a pair of mutually spaced plates carried by and secured to said tubular member,
- an insulating member carried by each plate of said pair of plates,
- a plurality of equally spaced contact blades carried by each insulating member and having an insulating strip disposed therebetween,
- a plurality of mutually spaced casings carried by and secured to said rotatable outer member,
- a support carried by each casing of said plurality of casings,
- a plurality of brush fingers carried by said support of each casing and cooperating with the contact blades of each insulating member as the outer member rotates about the inner member,
- a guide rail carried by each plate and having a groove formed therein,
- a guide block carried by each support engageable in the groove in each guide rail for invariably aligning the brush fingers with the contact blades upon movement of the casings past each plate of said pair of plates,
- 20 pin means carried by the support of each casing, and complementary means carried by each of said casings and cooperating with the pin means of each support for allowing vertical movement thereof and the brush fingers thereon to insure proper electrical contact between the brush fingers and the contact blades as the casings move past each plate of said pair of plates.

8. The combination of structure according to claim 7 wherein said complementary means includes a plurality of oppositely disposed brackets secured to each casing and provided with slots for receiving the terminal end of the pin means.

9. A multi-conductor slip ring construction suitable for use with a missile magazine having a fixed tubular member and a rotatable missile container and comprising a pair of supports, each support of said pair of supports having an elongated opening formed therein, a vertical movable brush assembly mounted on each support and within the opening therein, a plurality of brush fingers carried by said brush assembly, a contact assembly fixed to the other support of said pair of supports, a plurality of contact blades carried by and cooperating with said brush fingers, a plurality of pins carried by the brush assembly and loosely fitted into each support for mounting the brush assembly and brush fingers for vertical movement to insure proper electrical contact of the brush fingers with the contact blades upon rotation of said one support with respect to said other support, guide means on said brush assembly, and complementary guide means on said contact assembly and cooperating with the guide means on the brush assembly for aligning the brush fingers with the contact blades upon rotation of the brush assembly with respect to the contact assembly.

10. A multi-conductor slip ring construction comprising

- a contact assembly and a brush assembly,
- said contact assembly including a fixed support,
- a block composed of insulating material secured to said support,
- a plurality of contact blades carried by said block, an insulating divider disposed between pairs of contact blades of said plurality of contact blades,
- said brush assembly including a casing having an elongated opening formed therein,

an elongated member of insulating material mounted within the casing and disposed within said opening, a plurality of pins carried by said member and loosely fitted into the casing for allowing vertical movement of the member and brush fingers thereon as the brush fingers engage the contact blades,

5

guide means on the block, and complementary guide means on the member engageable with the guide means on the block for aligning the brush fingers and the contact blades upon rotation of the brush assembly with respect to the contact assembly.

10

11. A multi-conductor slip ring construction comprising

15

a contact assembly and a complementary brush assembly,

said contact assembly including a contact support, a block composed of insulating material secured to said block and having the outer edge curved throughout the length thereof,

20

a plurality of contact blades carried by said block, each blade of said plurality of blades extending beyond the curved edge of said block and having the outer edge thereof curved throughout the length thereof,

25

insulating separators carried by said block and separating the contact blades one from the other, said sep-

arators extending beyond the curved edges of the blades and having the outer edges thereof curved throughout the length thereof, said brush assembly cooperating with the contact assembly and including a casing having an elongated opening formed therein,

an elongated brush support composed of insulating material disposed within the casing and mounted within said opening,

a plurality of brush fingers carried by said brush support,

a plurality of pins carried by said brush support and disposed in mutual spaced relationship,

a plurality of aligning pairs of brackets carried by said casing, each pair of brackets of said plurality of pairs of brackets having a slot formed therein for receiving the terminal ends of one of each of the plurality of pins for allowing vertical movement of the brush support and the brush fingers with respect to said contact blades,

guide means on the block, and

complementary guide means on the brush support for aligning the brush fingers with the contact blades upon rotation of the brush assembly with respect to the contact assembly.
